UNITED STATES PATENT OFFICE.

ALBERT W. TINKER, OF CLEVELAND, OHIO.

CONCRETE VAULT CONSTRUCTION.

Application filed November 13, 1924. Serial No. 749,636.

This invention relates to concrete grave vaults and the general object is to provide a simply made, strong and durable grave vault which will withstand the corrosive effects of burial in the earth. A more specific object is to provide a seal for a grave vault which may be formed of plastic mineral material but which will not be in danger of being forced out by the weight 10 of the earth upon the top of the vault.

Other objects include the provision of a very simple and comparatively permanent cover band construction, whereby the plastic seal is retained within a groove between the 15 body wall and the cover for an indefinite period until the seal has entirely set.

In carrying out my invention, I employ reinforced hydraulic concrete and I preferably form both the vault and cover in substantially rectilinear figures. The vault body is in the nature of an oblong box having recessed corners to facilitate lifting the vault by means of straps and thereby obviate the necessity for handles. The cover 20 is in the nature of a flat slab having a groove about its under margin. The groove is preferably made by a rabbet overhung by a metal band, whereby the cover may be made substantially the same area as the top 25 of the vault.

One of the particular features of the invention lies in providing a marginal recess between the top of the body and the under face of the cover, preferably a deeper intermediate portion of the top groove, whereby, when the plastic material forming the seal is put in place and the cover lowered onto the vault, the deeper groove will hold 30 enough of the plastic material to form a perfect seal even if the material in the general groove has been extruded therefrom by the weight of earth resting upon the cover.

Another feature of the invention is the manner in which I attach the above mentioned band to the cover which generally consists of partially shearing and bending inwardly portions of the band members. These bent in portions are irregular in contour to insure a firm embracing by the concrete when set.

The manner whereby I have attained the above objects will become more apparent in the following description which pertains to the accompanying drawings, wherein I have 55 illustrated the preferred form of my inven-

tion. The essential characteristics will be summarized in the claims.

In the drawings Fig. 1 is a perspective of my assembled grave vault, a portion of the cover or lid being broken away; Fig. 2 is a bottom plan view of the lid; Fig. 3 is a fragmentary perspective of the band construction, a portion of the corner formed by the ends of two band members being shown in broken lines; Fig. 4 is a fragmentary cross-section through the margin of the cover of the box with the sealing material in place, as indicated by the line 4-4 on Fig. 2; Fig. 5 is a similar cross-section showing the lid resting on the brim of the vault proper; Fig. 6 is a diagrammatic view similar to Fig. 5 illustrating the sealing effect of the deeper groove in the sealing channel; Fig. 7 is a diagrammatic view of the band members in place, the mold for holding the members and receiving the concrete being shown in broken lines; Fig. 8 is a fragmentary cross-section through the mold and a portion of the cover as indicated by the line 8-8 on Fig. 7.

The vault which I show is that known as a top seal vault, the body of which comprises an oblong container 1 having a brim 2, side and end walls 3 and 4 and a bottom portion (not shown). The corners of the vault are shown beveled off as at 5, the beveled surfaces terminating in upper and lower abutments 6. The corners formed by these abutments serve in the place of handles whereby a continuous strap indicated in broken lines at S may be used in the manner indicated to lift the entire vault. Operating means such as hooks may engage such a strap on opposite sides as at S' for raising and lowering the vault. The vault proper it is to be understood may be suitably reinforced by metal members in any manner.

My vault cover is well adapted to be simply formed as shown in Figs. 7 and 8 upon a flat slab or block to which may be attached side-boards C which may be held in place by pivoted buttons B, (Fig. 8). My preferred cover band consists of an elongated strip 10 from which are partially sheared irregular shaped portions 11 T-shaped as shown which portions are bent inwardly as shown in Fig. 3, preferably at right angles, the inner end portion 12 serving to rigidly hold the bands in place while the connecting portion 13 is of sufficient 110

area to prevent the removal of the band by either force or corrosion before the seal has entirely set. When poured, the concrete forming the cover substantially fills the 5 apertures 11^a from which the material is removed to form the members 11, hence no undesirable appearance is given the cover and the attaching point of the member is further insulated from corrosion.

10 The extreme ease with which the cover may be formed and removed to a different location for setting after it has partially hardened will be evident from Figs. 7 and 8 wherein the top of the stationary mould 15 block B may be formed of a metal sheet B' having a plurality of inserts B² formed at the edge thereof. About the margin of this plate B' is a continuous rib member F having a raised central portion, substantially 20 circular in form as shown at G. This member F is separated from the general extent of the rib directly above the inserts B². The member F serves to support the band or more properly strip members 10 in place 25 previous to the pouring of the concrete. After the concrete is poured and leveled off at the top as shown in Fig. 8 and allowed to set, the side boards C are removed and hooks 8 may be inserted in the opening O 30 in the block or base B to a position beneath the insert and the whole cover may be removed to a different portion of the building where a number of covers may be piled one upon the other.

35 By forming the band 10 in separate sections as shown, a true corner may be formed which will not chip off as would concrete alone. Moreover, I have found that it is very difficult to form a bent strip in a single 40 plane to produce a flat cover, the difficulty being that either the ends or corners of an L or rectilinear shaped strip have a tendency to stand higher or lower than the general plane of the strip. The arrangement of the 45 members 11 shown may be of course varied to give a better support at the corners, but as a matter of fact I have found that the members need not be very close to the corners to effectively hold the strips in place.

50 Suitable reinforcement for the vault cover is of course provided and this reinforcement may hook over the inner ends of the members 11 to hold it in place and give it the trussed effect common to concrete reinforcement construction.

55 To seal the cover on the vault, the substantially rectangular recess 15 and the curved recess formed by the rib F of the mold is substantially filled with a plastic mineral material about as shown in Fig. 4 previous to placing the cover on the vault, the sealing effects obtained when the cover is placed thereon being shown in Fig. 5. In this figure it will be noted that the over-all width 60 of the recess 15 is slightly greater than the

thickness of the vault wall 2 and beveled for draft from the mold. I have found that this facilitates moulding as well as placing the cover on the vault without danger of chipping the concrete. Ordinarily the brim 70 of the vault is about in the center of the channel and the apertures at either side of the brim are not large enough to permit the sealing material to escape in any appreciable quantity while it is in the process of setting. However, if the concrete does become chipped or if the cover plate is shifted so that all of the aperture is at one side and the sealing material should be extruded from the cavity, there would still remain 80 sufficient sealing material in the deeper recess as shown in Fig. 6 to effect and maintain a perfect seal so long as the vault lasts.

85 It will be seen that I have provided a grave vault which may be very easily and cheaply formed in which a very effective seal is provided which will effectively close the vault to corrosive agencies for an indefinite period and in which the band for holding the seal in place may be cheaply 90 made capable of resisting corrosion for an adequate length of time. It is to be understood that after the vault is placed in the earth the forces tending to extrude the sealing material out of the recess are continually diminished by reason of the earth becoming packed about the vault. The band will then be held in position by the earth until completely corroded away and until 95 the rust and earth entirely replace it in the function of retaining the seal.

100 If desired I may prolong the life of the members 11 by making them T-shaped at both ends or of any other irregular shape; that of a T being preferred by reason of 105 being easy to bend up from the body of the strip.

Having thus described my invention, I claim:

110 1. A grave vault member having a continuous recess about the margin thereof, a continuous groove within said recess and separated from the sides thereof whereby when the recess contains plastic sealing material and coats with another vault member, the seal formed between the members is maintained by the plastic material entrapped in the groove by the coacting member irrespective of pressure between the two members.

115 2. A grave vault cover comprising a body portion having a shoulder at its margin for engaging the brim of a vault, a band about the periphery of the cover for forming a substantially continuous recess about the lower margin of the cover, and means including irregularly formed portions partially sheared from the strip and each projecting inwardly in a single plane disposed at intervals along the band whereby the 120

material forming the cover may hold the band in place.

3. In a grave vault in combination, a cover adapted to be formed from concrete having a rabbet at the edge thereof, a band extending around the cover and overlying the rabbet whereby a channel is formed and a continuous groove separated from the sides of the channel, said channel and groove being adapted to receive plastic sealing material.

4. A grave vault having continuous side and end walls, a cover therefor having a recess adjacent said side and end walls and coextensive with the upper surface thereof, said recess being wider than the vault wall to provide adequate clearance when the cover is put into place, and a continuous groove in the bottom of the recess whereby sealing material which is placed within the

recess and between the cover and vault wall will be entrapped in the groove in a continuous strip irrespective of the extrusion of the sealing material from the general recess consequent upon downward pressure on the cover.

5. A concrete grave vault member having a marginal recess, another concrete member having a brim portion of slightly less width than the recess and a groove in one of said members positioned between the sides of the recess whereby plastic sealing material may be retained between the two members substantially surrounded by concrete on all sides irrespective of pressure tending to force the members together.

In testimony whereof, I hereunto affix my signature.

ALBERT W. TINKER.
